Patented May 1, 1917.

UNITED STATES PATENT OFFICE.

RALPH A. SCHOENBERG, OF NEW YORK, N. Y.

ATTACHMENT-PLUG.

1,224,505.

Specification of Letters Patent.

Patented May 1, 1917.

Application filed April 22, 1916. Serial No. 92,980.

To all whom it may concern:

Be it known that I, RALPH A. SCHOENBERG, of New York city, in the county and State of New York, have invented a new and useful Attachment-Plug, of which the following is a specification.

The main object of my invention is to provide an attachment plug which is very light and very cheap and which is at the same time very efficient.

A feature of my invention consists in eliminating all of what has heretofore constituted the body of the attachment plug and using what may be termed a mere shell which may have an insulating lining if desired.

Other features relate to structural improvements.

Still other features will be pointed out below.

In the drawings:

Figure 1 is a central longitudinal section of a plug embodying my invention;

Fig. 2 is a top plan of the same;

Fig. 3 is a bottom plan of the same; and

Figs. 4 and 5 are sectional views of modifications.

Metal shell A has an outturned annular flange a at its upper end and an inturned 30 annular flange a' at its lower end and a circular bead a'' . It is also threaded at a^3 and has a pocket a^4 perforated at a^5 for the end of lead wire B, which end is soldered to the shell at the outside of the latter, that is, in 35 said pocket, this arrangement providing for soldering from the outside and at the same time avoiding interfering with the screwing of the plug into place.

A fiber cap or cover D has a port d for passage of lead wires B and B' and has a flange d' resting on flange a . Exterior insulation E in the form of a ring is held between a^2 and insulating ring F, the latter and flange d' being clamped to flange a by metal clamping ring G.

An inner perforated insulating fiber washer H rests on one side of flange a' and an outer perforated insulating fiber washer K bears against the other side of flange a' and these two washers are clamped together and to flange a' by tubular rivet M to which is soldered the bare end of wire B', rivet M being a center contact terminal which is supported by shell A through the medium of the washers and flange a' . An insulating washer N may be used in the opening of flange a' to

space washers K and H if such use is desired. Insulating fiber lining P may also be used for the shell if such use is desirable, this lining being held between cover D and washer H.

It will be clear that the usual core or body has been entirely dispensed with and that I use a mere shell which supports all the parts.

In Fig. 4 I show a modification as to the center contact structure in which washers H, 65 K and N have registering perforations forming a port R for the end R' of lead wire B', which end is bent around the head of center contact rivet M' which has prongs which are clenched to hold the washers to each other and to flange a' .

In Fig. 5 I use a tubular rivet M² which is 75 interiorly threaded to receive screw S, the end of wire B' being clamped between rivet M² and the head s of screw S.

What I claim is:

1. An attachment plug comprising a screw shell body, the inside of the shell forming the wall of an open chamber, said shell having a perforation in its side wall and serving as a terminal; a center contact mounted on, but insulated from, said shell; a cap for the shell provided with a port; and lead wires extending through said port, one extending through the perforation in the shell 85 and being permanently connected to the shell at the outside of the latter, and the other being permanently connected to said center contact.

2. An attachment plug having a screw 90 shell body, the inside of which is a hollow chamber, said shell having a perforation in its wall substantially below the top of the shell; a cap with a perforation conducting means to hold said cap to said shell; a lead wire passing through the perforation of said cap and through the perforation of said shell and connected mechanically to said shell at the outside of the latter; and exterior insulation for said shell between 100 said conducting means and the point of connection of said lead wire and said shell.

3. An attachment plug comprising a hollow screw shell, the inside of which forms the wall of a hollow chamber, said shell 105 having an inturned flange at one end and another flange at the other end and having a perforation; a center contact mounted on, but insulated from, said inturned flange; a cap with a port; means to attach said cap 110 to said other flange; a lead wire passing through said port and through said chamber

- and through said perforation and being mechanically connected to said shell at the outside thereof but within the outer circumference of the threaded portion thereof, and a second lead wire passing through said perforation and through said chamber and being connected to said center contact.
4. An attachment plug comprising a screw shell body, the inside of the shell forming the wall of an open chamber, said screw shell serving as a terminal; a center contact mounted on, but insulated from, said shell; a cap outside of said shell and provided with a port; means to fasten the cap to the shell; a lead wire passing through said port and through said chamber and mechanically connected to said shell at a point within the outer circumference of the threaded por-
- tion; and a second lead wire passing through said port and through said chamber and connected to said center contact.
5. An attachment plug comprising a screw shell body, the inside of which is a hollow chamber, said shell having an inturned flange; a center contact; insulating material connected with said center contact and supported by said flange; and a lead wire passing through said chamber and through said insulating material and being connected to said contact at the outside of the device.
6. An attachment plug comprising a shell with a flange; a formed up cap of insulating sheet material; and means to hold said cap to said flange.

RALPH A. SCHOENBERG.
